UNITED STATES PATENT OFFICE.

JOSEPH RAKONICK, OF ST. LOUIS, MISSOURI.

LAST.

1,067,136.

Specification of Letters Patent.

Patented July 8, 1913.

Application filed December 7, 1912. Serial No. 735,500.

To all whom it may concern:

Be it known that I, JOSEPH RAKONICK, a citizen of the United States, and residing at St. Louis, in the State of Missouri, have invented certain new and useful Improvements in Lasts, of which the following is a specification.

This invention relates to lasts and more particularly to lasts of the collapsible type.

10 The objects of this invention are to construct a last of the collapsible type provided with locking means for locking the last in extended position, which locking means will be simple in construction, easy to manipulate, and which construction will result in a last having great strength and which is cheap to manufacture.

Further objects will appear from the detail description taken in connection with 20 the accompanying drawing in which:

Figure 1 is a side elevation of a last in lengthened and locked position, part of the last being in section taken along its longitudinal center line. Fig. 2 is a view similar 25 to Fig. 1 but showing the last in collapsed position, Fig. 3 is an enlarged detail side elevation of the locking and latching means, Fig. 4 is a plan view of Fig. 3, Fig. 5 is a detail side elevation of a locking and latching means showing another embodiment of this invention, Fig. 6 is a plan view of Fig. 35 5, Fig. 7 is a detail perspective view of a part of the locking and latching means shown in Figs. 1 to 4 inclusive, and Fig. 8 is a detail of the latching lever.

Referring to the accompanying drawing, 10 designates a heel-part and 11 a fore-part of a hinged last of the knuckle joint type. The heel-part and fore-part have vertical kerfs 12 and 13 cut in their meeting edges, and these kerfs receive a plate 14 rigidly secured to the heel-part by means of pins 15 and 16 and pivoted to the fore-part by means of a pivot pin 17. The construction so far 40 described is well known to those skilled in the art.

The plate 14 is cut away on one side so as to provide a recess 18 adapted to receive one end of a link 19 which is pivoted on the 50 pin 16. A link 20 is pivoted in the kerf 13 on a pin 21 in the fore-part, which pin like the pins 15, 16 and 17, extends through the last. This link has a boss 22 so that its end will snugly fit the kerf 13. The links 19

and 20 are pivotally connected by a shouleder pin 23 so as to form a toggle connecting the heel-part and fore-part. When this toggle is straightened the last will be locked in lengthened position and when the toggle is broken the last can be collapsed. 55

The plate 14 is slotted as shown at 24 to receive a latching plate or lever 25 which is pivoted on the pin 17. This latching lever is provided with a curved slot 26 having an offset portion 27 and a cam portion 28. The 60 latching lever extends upwardly and is positioned between the toggle links 19 and 20 with the pin 23 working in the slot 26 and the offset portion 27. The ends of the pin 23 are riveted over so as to permanently connect the toggle links and the latching lever. 65

The parts are so constructed that when the last is lengthened the toggle will be straight and the pin 23 will be in the upper end of the slot in the latching lever as shown 70 in Figs. 1 and 3. When the parts are therefore in the position shown in Figs. 1 and 3, the toggle will lock the last lengthened and the latch 25 will operate to latch the toggle in locked position. In order to unlock the last 75 the latching lever is moved to the left, Figs. 1 and 3 to place the pin 23 in alinement with the slot 26. This movement of the lever will cause the cam portion 28 to engage the pin 23 and move it downwardly sufficiently to 80 break the toggle. The last can then be collapsed as shown in Fig. 2, the pin 23 moving downwardly in the slot 26 as the toggle breaks. When the last is again lengthened 85 and the toggle straightened to lock it in lengthened position, the lever 25 can be moved to the right, Figs. 1, 2 and 3 to latch the toggle in locked position. In practice the last is lengthened by grasping the fore-part and striking the heel-part on the bench. 90 This will cause the toggle to be rapidly straightened while the pin 23 in its outward movement will engage the cam 28 and operate to automatically move the lever 25 to the right, Figs. 1, 2 and 3, to latching position with the offset portion 27 in engagement with the pin 23. The slot in the latching lever is so constructed that the pin 23 moves freely therein as the toggle is broken and straightened. The last may therefore 95 be lengthened without manipulating the lever, and the last will automatically become locked when fully lengthened as de-

100

scribed above. After the last is locked and latched with the pin 23 in the offset portion 27, the parts will be maintained in locked position, since any collapsing movement given to the last will cause the locking and latching members to bind.

Referring now to Figs. 5 and 6 which disclose another embodiment of this invention, one side of the plate 14 is in this case cut away as shown at 30 to provide a recess for the lever 25, and the opposite side of the plate is cut away as shown at 31 to provide a recess for the toggle link 19. The toggle link 20 is in this case positioned between the link 19 and the lever 25, and is provided with two bosses 32, one on each side of the link. The lever 25 is similar in construction to that shown in Figs. 3 and 4 but the upper end of the slot 26 is square and angular as shown at 33.

It will be noted that in both embodiments the toggle links as well as the latching lever are positioned in and by the kerfs and in the same plane as the hinged plate 14. Furthermore the provision of the bosses or bosses on the toggle link 20 will cause this toggle link to make a snug fit with the kerf 13 in the fore-part. The locking and latching mechanism together with the plate 14 are therefore of uniform thickness as shown in Figs. 4 and 6 so that the kerfs can be made of uniform thickness and with a single tool, while the parts when assembled will make a snug fit with these kerfs so as to result in a last having an accurate and close fitting joint of great strength. The plate 14 as well as the links and lever can be made thin so that the whole can be placed in thin kerfs cut in the heel-part and fore-part, thereby retaining the strength of the last. It will be noted that the toggle links and the latching lever are mounted on and positioned by holes in a single plate 14. The parts can therefore be accurately constructed and fitted outside of the last so that when assembled in the last they will coöperate with the desired accuracy. The latching means is so arranged that the last can be readily unlocked with the thumb or finger without liability of injury to the operator. The locking and latching means is entirely automatic in its action when the last is extended and this operation is obtained without the use of springs.

It is obvious that various changes may be made in the details of construction without departing from this invention, and it is therefore to be understood that this invention is not to be limited to the specific construction shown and described.

Having thus described the invention what is claimed is:

1. A last comprising a heel-part and a fore-part connected for relative movement to lengthened and collapsed positions,

means constructed and arranged to lock the last in lengthened position against movement in either direction, and means for positively latching said locking means in locked position.

2. A last comprising a heel-part and a fore-part connected for relative movement to lengthened and collapsed positions, means constructed and arranged to lock the last in lengthened position, and means movable into and out of operative relation with respect to said locking means for latching said locking means in locked position, said latching means being constructed to unlock said locking means.

3. A last comprising a heel-part and a fore-part connected for relative movement to lengthened and collapsed positions, means constructed and arranged to lock the last in lengthened position, and means movable into and out of operative relation with respect to said locking means for latching said locking means in locked position, said latching means being in continuous engagement with said locking means and constructed to permit free movement of said locking means to locking position.

4. A last comprising a heel-part and a fore-part connected for relative movement to lengthened and collapsed positions, means connecting said last parts constructed and arranged to automatically lock the last in lengthened position when it is lengthened, and means movable into and out of operative relation with respect to said locking means for automatically latching said locking means in locked position when the last is lengthened.

5. A last comprising a heel-part and a fore-part connected for relative movement to lengthened and collapsed positions, a toggle connecting said parts constructed and arranged to lock the last in lengthened position, and means movable into and out of operative relation with respect to said toggle for latching said toggle in locked position.

6. A last comprising a heel-part and a fore-part connected for relative movement to lengthened and collapsed positions, a toggle connecting said parts constructed and arranged to lock the last in lengthened position, and means movable into and out of operative relation with respect to said toggle for breaking said toggle.

7. A last comprising a heel-part and a fore-part connected for relative movement to lengthened and collapsed positions, a toggle connecting said parts constructed and arranged to lock the last in lengthened position, and latching means for said toggle constructed and arranged to break said toggle.

8. A last comprising a heel-part and a fore-part connected for relative movement to lengthened and collapsed positions, means

for locking the last in lengthened position, a slotted lever having an offset portion and a cam portion, and a pin on said locking means co-operating with the slot in said lever.

9. A last comprising a heel-part and a fore-part arranged to swing on each other and provided with vertical kerfs in their meeting edges, combined with a plate hinging the heel-part and fore-part together and positioned in and fitting said kerfs, a locking device, and a latching device movable into and out of operative relation with respect to said locking device, said devices being positioned in the same plane as said plate and fitting and being positioned by said kerfs.

10. A last comprising a heel-part and a fore-part arranged to swing on each other and provided with vertical kerfs in their meeting edges, combined with a plate hinging the heel-part and fore-part together and positioned in said kerfs, a toggle connecting said heel-part and fore-part, and a latching lever for said toggle, said toggle and said lever being positioned in the same plane as said plate.

11. A last comprising a heel-part and a fore-part arranged to swing on each other about a pivoted center to lengthened and collapsed positions, means for locking the last in lengthened position, and a latching member for said locking means pivoted on the pivotal center of said last parts.

25 12. A last comprising a heel-part and a fore-part arranged to swing on each other and provided with vertical kerfs in their meeting edges, combined with a plate having a pivot hinging the heel-part and fore-part together and positioned in said kerfs, locking means, and a latching member for said locking means having the same pivot as said plate.

40

13. A last comprising a heel-part and a fore-part arranged to swing on each other and provided with vertical kerfs in their meeting edges, combined with a plate hinging said heel-part and fore-part together and positioned in said kerfs, locking means, and latching means for said locking means, said locking and latching means being mounted on said plate.

14. A last comprising a heel-part and a fore-part arranged to swing on each other and provided with vertical kerfs in their meeting edges, combined with a plate hinging the heel-part and fore-part together and fitting said kerfs, a toggle constructed and arranged to lock the last in lengthened position, said toggle being positioned in said kerfs and one end of said toggle being pivoted on said plate.

65 15. A last comprising a heel-part and a fore-part arranged to swing on each other and provided with vertical kerfs in their

meeting edges, combined with a plate hinging the heel-part and fore-part together and positioned in said kerfs, a toggle constructed and arranged to lock the last in lengthened position, and a plate for latching said toggle in locked position against movement in both directions. 70

16. A last comprising a heel-part and a fore-part arranged to swing on each other and provided with vertical kerfs in their meeting edges, combined with a plate hinging the heel-part and fore-part together and positioned in said kerfs, a toggle constructed and arranged to lock the last in lengthened position, and a latching plate for latching said toggle in locked position, said toggle and its latching plate standing vertically in said kerfs. 75 80

17. A last comprising a heel-part and a fore-part arranged to swing on each other and provided with vertical kerfs in their meeting edges, combined with a plate hinging the heel-part and fore-part together and positioned in said kerfs, a toggle constructed and arranged to lock the last in lengthened position, and a latching plate for latching said toggle in locked position, said toggle and its latching plate being pivoted on the plate hinging the heel-part and fore-part together. 85 93 95

18. A last comprising a heel-part and a fore-part arranged to swing on each other and provided with vertical kerfs in their meeting edges, combined with a plate hinging the heel-part and fore-part together and positioned in and fitting said kerfs, means for locking the last in lengthened position, and a plate standing vertically in one of said kerfs and adapted to engage and latch said locking means. 100 105

19. A last comprising a heel-part and a fore-part arranged to swing on each other and provided with vertical kerfs in their meeting edges, combined with a plate hinging the heel-part and fore-part together and positioned in and fitting said kerfs, a locking device for locking the last in lengthened position, and a latching device for said locking device, said plate having means for positioning said locking and latching devices in said kerfs. 115

20. A last comprising a heel-part and a fore-part arranged to swing on each other and provided with vertical kerfs in their meeting edges, combined with a plate hinging the heel-part and fore-part together and positioned in and fitting said kerfs, a toggle connecting said last parts and positioned in said kerfs constructed to lock the last in lengthened position, and a latching lever pivoted in one of said kerfs and adapted to latch said toggle in lengthened position. 120 125

21. A last comprising a heel-part and a fore-part arranged to swing on each other and provided with vertical kerfs in their 180.

meeting edges, combined with a plate hinging the heel-part and fore-part together and positioned in and fitting said kerfs, a toggle connecting said last parts and positioned in said kerfs, constructed to lock the last in lengthened position, and a latching lever pivoted in one of said kerfs and adapted to latch said toggle in lengthened position, said

toggle and said lever being pivoted on said plate.

In testimony whereof I affix my signature in the presence of two witnesses.

JOSEPH RAKONICK.
